CONCRETE STAIR FORM

Adam F. Pollman, Milwaukee, Wis.

Application April 2, 1948, Serial No. 18,539

5 Claims. (Cl. 25—118)

1

This invention relates to concrete forms and has more particular reference to a sectional or knockdown form especially adapted for the pouring of concrete stair units, but which is also useful for the laying of concrete footings and side-walks.

The primary object of this invention resides in the provision of a concrete stair form capable of being readily assembled in a number of different ways from elongated structural elements having detachable connections with one another to define different types and sizes of stair units.

More specifically this invention has as its object the provision of a concrete stair form which comprises a plurality of channel-shaped structural elements which may be readily connected with one another on location to provide a series of substantially U-shaped frames superimposed one upon the other with certain of the elements offset with relation to one another to define the risers of a stair unit, and with the remaining elements defining the sides of the form.

With the above and other objects in view, which will appear as the description proceeds, this invention resides in the novel construction, combination and arrangement of parts substantially as hereinafter described and more particularly defined by the appended claims, it being understood that such changes in the precise embodiment of the hereindisclosed invention may be made as come within the scope of the claims.

The accompanying drawings illustrate two complete examples of the physical embodiment of the invention constructed according to the best modes so far devised for the practical application of the principles thereof, and in which:

Figure 1 is a perspective view of one type of concrete stair form made in accordance with the principles of this invention;

Figure 2 is an enlarged perspective view of a front corner portion of the form shown in Figure 1;

Figure 3 is an enlarged perspective view of the rear portion of the form shown in Figure 1 and illustrating the means for holding the elements of the form against shifting relative to one another;

Figure 3a is a fragmentary sectional view taken through Figure 3 along the plane of the line 3a—3a;

Figure 4 is a perspective view similar to Figure 1 but illustrating the elements of the form connected in a different manner to produce a form for a side step stair unit;

Figure 5 is an enlarged fragmentary perspec-

2

tive view of a portion of the form shown in Figure 4;

Figure 6 is a plan view illustrating a modified type of holding means for the elements of the form; and

Figure 7 is a perspective view of the connector or clamping element shown in Figure 6.

Referring now more particularly to the accompanying drawings in which like numerals indicate like parts, the numeral 5 in Figure 1 generally designates one type of stair form which may be produced by the sectional form construction of this invention. The form is comprised of a number of lengths of channel-shaped elements detachably connected together to provide a front step stair unit having two risers.

This form, as well as others for different types of stair units described later, is constructed from two basic types of elongated channel members 6 and 7 which are preferably bent up from sheet metal so as to be light in weight. The channel-shaped members 6 have their flanges 8 extended at opposite ends as at 9, and the flange to flange distance of these members is slightly greater than the distance between the flanges 10 on the channel-shaped members 7. This allows one of the channel members 7 to be disposed crosswise of the ends of a pair of channel members 6 with the flanges of the channel member 7 received between the flange extensions 9 on the adjacent ends of the channel members 6.

The flange extensions 9 on the channel members 6 have vertically aligning holes 12 therein which may be brought into register with pairs of vertically aligning holes 13 in the top and bottom flanges of one of the channel members 7 so that insertion of a pin 14 from top to bottom through the holes 12 of the flange extensions and the aligning holes 13 in the flanges 10 of the channel members 7 lock the members 6 and 7 together. It is to be understood that the flanges of the channel members 7 have a number of sets of vertically aligning holes 13, preferably spaced apart equal distances along the length of the members.

By way of example, the sets of vertically aligning holes 13 in the flanges 10 of the members 7 may be assumed to be located 6" apart to enable relatively close adjustment of the spacing between the channel members 6. Hence, when two channels 6 of equal length and arranged back to back are connected to one of the channels 7 in the manner described, they define the legs of a U-shaped frame, with the spacing between the 55 legs corresponding to the desired width of a front

step stair unit of the type shown in Figure 1. Since the flanges 10 of the member 7 must also face outwardly of the frame, it will be apparent that the upright webs of the channel members 6 define portions of the sides of the stair unit to be poured while the upright web of the channel member 7 defines one of the risers of the stair unit.

The channels 7 may all be of the same length if desired, but the channels 6 must be provided in pairs whose lengths vary by a predetermined dimension corresponding to a more or less standard depth of stair tread. In the two-step stair form illustrated in Figure 1 two U-shaped frames are required. The channels 6 defining the legs of each frame are spaced equal distances apart to enable the frames to be superimposed one upon the other, but the legs of the upper frame are shorter than those of the frame therebeneath by an amount corresponding to the depth of stair tread. Hence, when the outer or free ends of the legs of the two frames are brought into vertical alignment, the webs of the channels 7 are offset to lie in different vertical planes spaced apart a distance corresponding to the depth of stair tread to define the two risers of the form, while the co-planar webs of the superimposed channels 6 define the opposite sides of the form.

The flanges 8 of the channels 6 also have sets of vertically aligning holes 15 along their length with the spacing between them and the holes 12 corresponding to the spacing of the holes 13. Consequently if the standard depth of stair tread may be assumed to be 12", the spacing of the holes in the flanges of the channels is one-half the depth of tread. Thus it will be apparent that the lengths of the channels 6 are substantially multiples of the depth of stair tread, or 12".

With this relationship between the side channels 6 of the form shown in Figure 1, the pins 14 which secure the channels 6 and 7 of the upper U-shaped frame together are enabled to pass through the holes 15 in the upper flanges 8 of the members 6 therebeneath so as to not only connect the channels of each individual frame with one another but to connect the frames themselves to one another, as best shown in Figure 2. This is possible since all the holes 12 and 15 of the channels 6 align vertically with one another in the operative position of the form.

The webs of the superimposed channels 6 are maintained in co-planar relationship partly by means of the pins 14 connecting the legs of each frame with their cross member 7, partly by a clamping device generally designated 20, one such clamping device being disposed adjacent to each side of the form near the outer or open ends of the U-shaped frames.

Each of these clamping devices comprises a rod-like standard 21 preferably made of piping having a foot 22 welded or otherwise fixed to one end thereof normal to the axis of the standard 21. The foot 22 is adapted to lie flat upon the ground and it is apertured as at 23 a distance outwardly of the standard to receive a stake 24 so that when the stake is driven into the ground it will anchor the foot 22 flat-wise upon the ground and hold the standard 21 in an upright position.

A plurality of flat clamping plates 25 is provided for each clamping device. These plates have apertures 26 substantially centrally thereof to enable the same to be slid up and down the standard 21 for disposition of the plates at any desired elevation on the standards and normal thereto. Each of these clamping plates has a

stud 27 fixed thereto at one end of the plate substantially normal to the plane of the plate and projecting from opposite sides thereof. These studs are adapted to engage in the apertures 15 of the legs 6 of the U-shaped frames and serve to connect the rear sides of the form with the upright standard 21. Locking screws 28 threaded edgewise into the opposite ends of each plate may be brought to bear against the exterior of the upright standard 21 to lock the clamping plates in operative positions upon the standard.

In use with a two step form of the type shown in Figure 1, therefore, three clamping plates are assembled upon each upright standard 21 with the lower flange of the bottom side channel 6 resting flatwise on the lowermost clamping plate and with the studs 27 of this plate projecting upwardly into one of the apertures 15 in said flange. The intermediate clamping plate is disposed to rest flatwise upon the inner surface of the lower flange 8 of the upper side channel with its stud 27 projecting through the aligning holes 15 in the adjacent flanges of the side channels. The third clamping plate is engaged flatwise on the top of the uppermost flange of the top side channel with its stud 27 projecting downwardly into one of the holes 15 therein.

Hence, when the clamping plates are locked to the standards 21 in the positions described, by means of the locking screws 28, the outer ends of the side members 6 remote from their cross members 7 are securely held against motion relative to one another, and the webs of the side channels are securely maintained in co-planar relationship.

Similar clamping devices 30 are adapted to be employed at the front of the form, and the clamping plates 25 thereon embrace the flanges 10 of the lowermost riser forming channel 7 to minimize the possibility of shifting of the form when concrete is poured therein and to cooperate with the clamping devices 20 in holding the open ends of the U-shaped frames against the wall of a building 31 beneath a door opening 32 therein.

If further reinforcement of the form is desired a tie member 34 may be employed. This tie member is preferably one of the channels 7 as shown and it is disposed across the top of the uppermost U-shaped frame adjacent to the open end thereof with its back or web facing the wall of the building for which the stair unit is intended. Additional pins 14 passing through the vertically aligned holes in the flanges of the tie member to have their lower ends received in the apertures 12 of the side channels 6 secure the tie member in place so as to prevent spreading of the sides of the form.

Diagonally extending straps 36 having parallel upper and lower flanges 37 and 38 respectively to overlie the top flange of the tie member and the top flanges of the uppermost side channels 6 may be employed, if desired, to reinforce the connection between the tie member 34 and the topmost U-shaped frame. These diagonal straps 36 are secured to the tie member by the pins 14 passing through suitable apertures in the upper flanges 37 of the straps, and the studs 27 of the topmost clamping plates 25 passing upwardly through suitable apertures in the lower flanges 38 of the straps.

When assembled as in Figure 1, the form defines the opposite side walls and the risers of the stair unit, as stated hereinbefore. Since the ends of the webs of the channels 6 are spaced

a slight distance from the wall of the building by the flange extensions, thin angle-shaped sheet metal retainers 39 are employed to prevent concrete from leaking out of these spaces. Each retainer has one leg disposed over the webs of the channels 6 at the inside of the form, and the other leg extends behind the ends of the channels 6 to the exterior of the form and to lie flat against the wall of the building.

The entire top of the form, however, is open, as is the tread of the lower step, to enable trowelling of concrete poured into the form to a smooth finish at the tread of the lower step and the top or platform of the stair unit.

It is to be observed that since the riser forming channels 7 are narrower than the side channels 6 and the flange extensions 9 on the side channels embrace the riser forming channels, the top of each riser is spaced a definite distance beneath the level of the underside of the next higher riser, this distance being at least twice the thickness of the metal from which the channels are formed.

One of the features of the step form of this invention is the easy adjustability of the channels from which it is assembled. This adjustability applies not only to dimensions of the stair unit which it is to define, but also to the style of the stair unit. Hence, by employing the proper lengths of channels 6, forms may be assembled to produce stair units having only one riser, or three or more risers.

Likewise, a side stair unit like that illustrated in Figure 4 may be quickly assembled from the channels 6 and 7. In this case, the channels are connected together to define three superimposed U-shaped frames with the channels 7 offset relative to one another as before, so as to define the risers for the three steps of the unit. Three additional superimposed channels 7' identical to the channels 7 and of equal length however, are connected to the ends of the channels 6, of different lengths, remote from the riser forming members 7. The channels 7 and 7' therefore define the legs of each of the superimposed U-shaped frames, and the outer or open ends of these frames are adapted to abut the wall 31 of the building beneath the door opening 32 therein as in the previous instance but with the channel members 7 defining risers perpendicularly to the wall 31.

Support for the free ends of the riser forming channels 7 is afforded by means of a diagonal brace 40. The brace 40 is preferably in the form of an angle iron having an upstanding leg 41, and having a series of substantially triangular plates 42 secured flatwise thereto, one for each riser forming channel 7. Each of these plates has a right angle flange 43 of sufficient length as to rest on the top flange of one of the risers and to bear against the underside of the lower flange of the next higher riser.

Hence, the flanges 43 extend over the ends of the treads adjacent to the building. Pins 45 are inserted into the apertures 13 in the flanges near the outer ends of the risers 7 and through aligning apertures 46 in the flanges 43 to provide for attachment of the risers to the brace 40, so that each riser is supported from the 70 riser therebeneath.

The brace 40 cooperates with an angle-shaped tie member 47 having a horizontal flange 49 received flatwise upon the flange 43 of the uppermost plate 42 at one end, and upon the upper 75

flange of the topmost channel 7' at the opposite end of the tie member. The tie member 47 in this case may be secured to the topmost channel 7' by one of the pins 14 passing through a hole in the horizontal flange 49 of the tie member and received in one of the holes 13 in the flange of the channel 7'; while the opposite end of the tie member has a pair of holes therein aligning with the two holes in the flange 43 of the uppermost plate 42 to receive a short bolt 52 and another one of the pins 14. The pin 14 in this case passes through the angle, the flange 43, both flanges of the topmost riser 7, and the top flange of the channel 7 therebeneath.

Clamping devices 20 and 30 may again be employed to preclude shifting of the sides and front of the form as previously described.

The modified form of clamping element shown in Figures 6 and 7 is adapted to be substituted for the plate 25 and, of course, is used for the same purpose, namely, to rigidly connect the channel members with the upright standards 21. The clamping element in this case features easier detachability and comprises a U-shaped strap 53 of a size to loosely embrace the standard 21. The legs 54 and 55 of the U-shaped strap are adapted to lie at opposite sides of the standard 21 and are extended outwardly far enough to wholly receive the standard 21 therebetween.

The legs have aligning apertures 56 in their outer ends to receive either arm 57 of a lever 58 which confines the standard in the bottom of the strap when operatively connected with the legs of the strap. The arms of the lever have a round cross section and each arm has a medial portion 59 thereof offset so as to be eccentric to the axis of its arm.

Washers 60, one fixed to each arm as by welding, and adjacent to the juncture between the arms, determine the extent to which the arms may be inserted into the aligning holes 56. In addition, these washers locate the eccentric portion 59 of either arm inserted into the holes 56 exactly midway between the legs 54 and 55 of the strap, and hence directly opposite the standard between the legs.

With the strap in place embracing the standard, therefore, it is only necessary to insert one of the arms of the lever into the holes in the outer ends of the legs of the strap, and with the concave side of the eccentric 59 on said arm facing the standard. Then, upon rotation of the lever by means of the handle afforded by the other arm, the eccentric portion of the arm is brought to bear against the standard with a force which increases to maximum at 180° rotation of the lever from its inserting and withdrawing position. The force with which the lever arm is thus engaged with the standard is more than adequate to hold the U-shaped strap in any desired position along the length of the standard.

The U-shaped strap is connectible with the channels of the form by means of studs 62 welded or otherwise secured to a bar 63 which in turn is welded edgewise to the side of one of the legs of the strap. The studs project from the opposite faces of the bar, and their spacing corresponds to the spacing of the holes in the flanges of the channels 6, 7 and 7' so that the engagement of both studs in adjacent holes in the flanges of the channels is required to anchor the channels to the standard 21.

The clamping elements shown in Figures 6

and 7 are especially useful for joining the longitudinally telescoped ends of channels 6 and 7 telescoped together and arranged in opposite back to back relationship for the provision of concrete footing or sidewalk forms.

As shown in Figure 4, the standards 21 may be employed without the feet 22, and in this event the standards themselves are driven into the ground adjacent to the form to provide the necessary rigidity for the standards.

It will also be appreciated that, while only two types of stair units have been disclosed in Figures 1 and 4, forms for other types of stair units having opposing sets of steps, as well as steps on three sides thereof, may be readily assembled from the channel members 6 and 7.

From the foregoing description taken in connection with the accompanying drawings, it will be apparent to those skilled in the art that this invention provides an exceptionally simple sectional form construction for concrete stair units which features adjustability to enable considerable variation in dimensions of the stair unit, as well as versatility in enabling assembly of forms for a number of different types of stair units.

What I claimed as my invention is:

1. A concrete form characterized by: elongated channel-shaped members each having parallel flanges spaced apart a common distance and provided with equispaced aligning sets of holes; other elongated channel-shaped members each having parallel flanges spaced apart a distance greater than the flanges of the first designated channel members an amount substantially equal to twice the flange thickness; apertured flange portions extended lengthwise from one end of each flange of each of said other channel members and adapted to engage over and under the flanges of said first designated channel members with the apertures of the flange extensions in register with sets of vertically aligning holes in the flanges of said first designated channel members; and means engageable in said registering apertures for locking the channel members together.

2. A sectional form into which concrete is adapted to be poured to produce a stair unit comprising: a pair of superimposed U-shaped frames having elongated channel-shaped legs and backs with the flanges thereof turned outwardly of the form, the webs of the channel-shaped backs being wider than the webs of the channel-shaped legs by an amount substantially equal to twice the thickness of the flanges of the channel-shaped backs, the back and one leg of the upper frame overlying the back and corresponding leg of the frame therebeneath, and the back of the upper frame being shorter than the back of the frame therebeneath to dispose the remaining legs of the frames in offset relationship so that said offset legs provide stair risers for the form, while the first-named legs and the backs of the frames provide upright angularly disposed sides for the form; and detachable connections between the backs of the frames and their respective legs and between the frames for holding the same against shifting relative to one another, said detachable connections com-

prising flange extensions on the opposite ends of the channel-shaped backs overlying and underlying the flanges of the legs so that the top of the leg which defines the lowest stair riser is on a lower elevation than the bottom of the leg which defines the next higher riser, and removable pins passing through aligned holes in the flange extensions and flanges.

3. The form set forth in claim 2 further characterized by the provision of a diagonal member connected with said offset legs adjacent to their outer ends for holding the same in said offset relationship.

4. The form of claim 3 further characterized by the provision of a tie member connected across the open end of the top U-shaped frame and cooperating with said diagonal member to preclude shifting of the frame parts relative to one another.

5. A sectional form for a poured concrete stair unit characterized by: a pair of spaced apart side forming channel members arranged back-to-back; a second pair of spaced apart side forming channel members shorter than the first pair by the depth of a stair tread, said second pair of channel members also being arranged back-to-back and being superimposed upon the first pair; a channel shaped riser extending crosswise of each pair of said back-to-back channel members directly across one end thereof with the flanges of the risers turned outwardly of the form, the webs of said risers being narrower than the webs of the channel members by twice the thickness of the flanges of said channel members; and readily detachable connections between the superimposed side forming channel members and the risers holding the same in proper step forming relation, said connections comprising extensions of the flanges on the ends of the side forming channel members adjacent to the risers overlying and underlying the flanges on the risers so that the top of each riser is a definite distance below the level of the underside of the next higher riser, and pins passing through aligned holes in said flange extensions and the flanges of the risers.
